United States Patent Office

Des. 194,348
Patented Jan. 8, 1963

194,348

WINDOW LOCK

Robert J. Deisenroth, Elkhart, Ind., assignor to Excel Corporation, Elkhart, Ind., a corporation of Indiana

Filed Aug. 23, 1960, Ser. No. 61,867

Term of patent 14 years

(Cl. D10—10)

FIG. 1

FIG. 3

FIG. 2

FIGURE 1 is a perspective view of a window lock showing my new design;

FIGURE 2 is a perspective view thereof, viewed from the bottom right and opposite side of FIGURE 1;

FIGURE 3 is a front elevational view thereof.

I claim:

The ornamental design for a window lock, substantially as shown.
